Primary Examiner — Marie D. Fast Horse(74) *Attorney, Agent, or Firm* — Marshall, Gerstein & Borun LLP(57) **CLAIM**

The ornamental design for a POS terminal, as shown and described.

DESCRIPTION

FIG. 1 is a front, top, and right-side orthographic view of a POS terminal showing the new design.

FIG. 2 is a front elevation view of the POS terminal.

FIG. 3 is a rear elevation view of the POS terminal.

FIG. 4 is a left-side elevation view of the POS terminal.

FIG. 5 is a right-side elevation view of the POS terminal.

FIG. 6 is a top plan view of the POS terminal.

FIG. 7 is a bottom plan view of the POS terminal.

FIG. 8 is a rear, top, and right-side orthographic view of the POS terminal shown with the screen in a tilted position for use.

FIG. 9 is a rear, top, and right-side orthographic view of the POS terminal; and,

FIG. 10 is a rear, bottom, and right-side orthographic view of the POS terminal.
